UNITED STATES PATENT OFFICE

2,579,670

HYDRAULIC PRESSURE TRANSFORMER

Eric Georg Hjärpe, Goteborg, Sweden, assignor to
Aktiebolaget Svenska Kullagerfabriken, Gote-
borg, Sweden, a corporation of Sweden

Application March 24, 1949, Serial No. 83,206
In Sweden April 2, 1948

7 Claims. (Cl. 103—49)

1

The present invention relates to a device for transforming the pressure of at least part of a driving liquid to a higher specific pressure, for instance for driving a mechanism which for its function requires a higher liquid pressure than that available. Since the quantity of pressure liquid consumed is, as a rule very variable, it is necessary that the quantity of liquid shall be variable from the maximum down to nil.

Certain devices which have been proposed for this purpose have been provided with a relief valve through which the surplus liquid not used for driving purposes may escape. As disadvantage with all systems using relief valves is however that part of the input is lost in the form of heat which is transferred to the liquid, the viscosity of which is hereby usually considerably altered.

In other systems a part of the available fluid is used to drive a liquid motor, which is directly connected to a high pressure pump. If the motor is of rotary type the efficiency will be quite low, and the effect which is lost is transformed to heat, which in this case also is transferred to the liquid.

Devices having reciprocating pistons as hitherto used are rather complicated and expensive, since the pistons are mutually mechanically interconnected, as is also the case with the governing valves. Such devices also have certain other disadvantages such as uneven delivery, etc.

The device according to the present invention is governed preferably entirely by hydraulic means by valves which are also hydraulically governed. The whole aggregate will thus be simple and flexible and there will be hardly any wear on the parts.

An embodiment of the invention is shown on the accompanying drawings wherein Figs. 1 to 5 are like fragmentary sectional views showing the respective positions of the parts of the transformer during different phases of the cycle. The numeral 1 indicates the inlet line for a pressure liquid. From the inlet line the fluid flows through channels 2 and 3 to a pair of ball valves 4 and 5. These valves are opened by the pressure of the liquid, permitting the liquid to obtain access through channels 41 and 42 to the minor cylinders 6 and 7 of a pair of differential pistons, where it acts on the pistons 8 and 9 moveable in these cylinders. The pistons are thus caused to assume their lower positions as long as there are no other forces acting upon them. The pressure liquid is also led from the inlet 1 to a valve chamber 10 and to another valve chamber 11 in a pair of piston valves 12 and 13.

When the position is that shown in Fig. 1 the liquid is led from the valve chamber 10 through a channel 14 to a valve chamber 15. The valve chamber 16 at the other end of the piston valve

2

13 is in communication with an outlet 17 through a channel 18, a chamber 19 in the valve 12, a channel 35, an annular channel 36 which surrounds the valve 13 and a channel 34. In the position shown the liquid continues from the valve chamber 14 through a channel 20 to the working cylinder 21 of one of the differential pistons, where it exerts a pressure on the piston 22 which may, for example, be five times as great as the pressure exerted by the liquid on the piston 9, if the areas of the pistons are as 5:1. Equilibrium will therefore not be attained until until the piston unit 9—22 has moved so fast that the specific pressure in the cylinder 7 has increased to five times the specific pressure of the liquid entering through the inlet duct 1.

The liquid in the smaller cylinder 7 is thus forced past a ball valve 23 out into a duct 24 leading to a working cylinder or the like.

20 The ball valves 5 and 25 are kept closed by the higher liquid pressure. When the piston unit 9—22 has moved so far that it opens a channel 26 leading from the cylinder 21 to a valve chamber 27 to the right of the valve 12, the liquid is led through this channel to the said valve chamber and forces the valve 12 towards the left. This movement is made possible since the valve chamber 28 at the left end of the valve is in communication with the outlet 17 through the channel 29, the upper part 30 of the cylinder and the channel 31. The position is now that shown in Fig. 2.

25 The displacement of the valve 12 puts the valve chamber 19 in communication with the inlet 1 and pressure liquid flows from the inlet through the channel 18 to the valve chamber 16 and forces the valve 13 to the right which is possible since the valve chamber 15 is in communication with the outlet 17 through the channel 14, the valve chamber 10, a channel 32 leading from the latter to an annular channel 33 which surrounds the valve 13 and the channel 34.

30 The displacement of the valve 13 (see Fig. 3) puts a valve chamber 37 in the valve 13 in communication with the inlet 1 and the cylinder 21 is put in communication with the outlet 17 through the channel 20, valve chamber 11, an annular channel 36 surrounding the valve 13 and the channel 34. The pressure liquid now flows from the channel 1 through the valve chamber 19, channel 2, valve chamber 37 and a channel 38 to a working cylinder 39, where it exerts pressure on a piston 40, which is connected to the piston 8. The pressure liquid then forces the piston unit 8—40 in a direction towards the cylinder 6 in which the specific pressure increases to five times the pressure of the liquid entering through the inlet 1. The liquid in the cylinder 6 is forced out of the cylinder past the ball valve 25 and out into the duct 24 leading to the place

of consumption. The ball valves 23 and 4 are then held in a closed position by the high pressure.

Since the cylinder 21 as above mentioned is in communication with the outlet while the pressure in the cylinder 7 is the same as that in the inlet 1 the piston unit 9-22 is forced in the direction from the cylinder 7 to its lower end position. The position is now that shown in Fig. 3.

When the piston unit 8-40 (which has above been said to be on its way up) has gone so far that communication is opened between the cylinder 39 and the channel 29, liquid flows through this channel to the valve chamber 28 and forces the valve 12 towards the right back to its original position, which is possible since the valve chamber 27 at the other end of the valve by the previously mentioned downward movement of the piston unit 9-22 has been put into communication with the outlet 17 through the channel 26, a channel 43 which connects the cylinder parts 30 and 44, the upper part 44 of the cylinder, the channel 43, the cylinder part 30 and the channel 31.

By the displacement of the valve 12 towards the right (Fig. 4) the valve chamber 10 has again been put into communication with the inlet 1 and the liquid flows through the channel 14 to the valve chamber 15 and displaces the valve 13 back to its original position, since the valve chamber 16 is again in communication with the outlet 17 through the channel 18, the valve chamber 19, the channel 35, the annular channel 36 and the channel 34. The position of the valves is now that shown in Fig. 5. The liquid now again flows from the inlet 1 through the valve chamber 10, the channel 2, the valve chamber 11 and channel 20 to the cylinder 21 and displaces the piston unit 9-22 upwards so that the specific pressure increases in the cylinder 7 to the higher pressure and holds the ball valves 5 and 25 closed, the liquid passing the ball valve 23 into the duct 24. The pressure in the cylinder 6 will be the same as that in the inlet 1 and forces the piston unit 8-40 in the direction from the cylinder 6, since the cylinder 39 is again in communication with the outlet 17 through the channel 38, valve chamber 37 and channel 34. The position of all parts is now once more that shown in Fig. 1.

The working cycle described above is continuously repeated as long as liquid is removed from the outlet duct 24. The speed of the piston units 9-22 and 6-40 is governed by the liquid consumption as long as the capacity of the apparatus is not exceeded.

In order to prevent momentary drops in pressure in the duct 24 when the valve 13 is reversed from one end position to the other the valve chamber 11 and 37 in the valve are never cut off from the inlet at the same time. In other words the cylinders 21 and 39 are never pressureless simultaneously.

When the device is used for feeding machines with very considerable variations in liquid consumption, for instance machines having alternately a slower feed and swift reverse it is of advantage to introduce a reversing valve between the device and the machine for automatically connecting the machine to the high pressure line or the low pressure line as required. For quick maneuvering when the consumption is great but the pressure not high, the machine is thus automatically connected directly to the low pres-

sure line. The transformer then remains stationary. When the machine is running with ordinary feed during the working phase when higher pressure is required but the liquid consumption is much lower it is automatically connected to the high pressure line from the apparatus.

Having thus described my invention I claim and desire to secure the following by Letters Patent:

1. A hydraulic pressure transformer having a plurality of differential pistons, each reciprocating in a low pressure cylinder and a high pressure cylinder, means for putting the low pressure cylinders into intermittent communication with a primary duct for pressure liquid and means for intermittently putting the high pressure cylinders alternately into communication with a low pressure duct such as the said primary duct and a high pressure duct, the movement of the said differential pistons being controlled by automatically controlled governing means in such a way that liquid is always being delivered from at least one of the high pressure cylinders, the movements of the said governing means being hydraulically controlled by the movements of the said differential pistons.

2. Hydraulic pressure transformer according to claim 1, characterized thereby that each high pressure cylinder is provided with a check valve, through which it is intermittently put into communication with a common pressure line.

3. Hydraulic pressure transformer according to claim 1, characterized by a check valve between the low pressure duct and the high pressure cylinder of the differential piston.

4. Hydraulic pressure transformer according to claim 3 characterized thereby that each high pressure cylinder is provided with a check valve through which the cylinder is intermittently put into communication with a common pressure line.

5. Hydraulic pressure transformer according to claim 1 characterized by piston valve means for distributing the fluid to the low pressure cylinders.

6. Hydraulic pressure transformer according to claim 1, characterized thereby that the control means includes channels from the low pressure cylinders, the mouths of the channels being positioned so as to be uncovered to the piston actuating hydraulic pressure only when the pistons have reached predetermined positions in the pressure strokes.

7. Hydraulic pressure transformer according to claim 6 wherein the piston valve means is operatively connected by channels to the low pressure cylinders, the mouths of the channel being positioned so as to be uncovered to the piston actuating hydraulic pressure only when the pistons have reached predetermined positions in the pressure strokes.
